US00D589979S

(12) **United States Design Patent**
Andre et al.

(10) **Patent No.:** US D589,979 S
(45) **Date of Patent:** ** Apr. 7, 2009

(54) **ELECTRONIC DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, San Francisco, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US)

(73) Assignee: **Apple Inc.**, Cupertino, CA (US)

(**) Term: **14 Years**

(21) Appl. No.: **29/298,307**

(22) Filed: **Dec. 3, 2007**

Related U.S. Application Data

(63) Continuation of application No. 29/269,781, filed on Dec. 8, 2006, now Pat. No. Des. 558,784, which is a continuation of application No. 29/242,458, filed on Nov. 9, 2005, now Pat. No. Des. 538,822, which is a continuation of application No. 29/208,302, filed on Jun. 24, 2004, now Pat. No. Des. 516,576.

(57) **CLAIM**

We claim the ornamental design for an electronic device, substantially as shown and described.

DESCRIPTION

FIG. 1 is a perspective view of an electronic device showing our new design.

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left view thereof.

The dotted lines in the figures illustrate environment and do not form any part of the claimed design.
